UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

CONTACT STRUCTURE FOR ELECTRIC SWITCHES.

Application filed May 29, 1925. Serial No. 33,804.

This invention relates to electric switches and has for an object the provision of means to improve the contact between the separable switch members when they are traversed by a heavy current.

A further object is generally to improve the construction and operation of electric switches.

Fig. 1 is a side elevation, partly in section, of the current-conducting members of an electric switch embodying the invention.

Fig. 2 is a transverse section of the shank-portion of the brush-member, taken along line 2-2 of Fig. 1.

Fig. 3 is a detail of a modified arrangement of the stationary and movable switch members of Fig. 1.

The magnetic reaction of an electric current traversing a sinuous conductor tends to straighten the conductor. This principle is herein utilized to improve the contact between the stationary and movable switch members under load.

As here shown the invention is incorporated in a down-break switch having stationary switch members including fixed conducting studs 10 inclosed in insulating bushings 12. Stationary contact members 14 are fixed to the lower ends of said studs and are provided with approximately horizontal contact faces 16 against which the movable switch member is adapted to abut.

The movable switch member includes a relatively rigid conducting bar 18 which is disposed beneath and is extended between the stationary switch members; and brush, or contact, members 20 are fixed to the ends of said bar and are adapted to engage said stationary contact members 14.

Said brush members comprise a plurality of laminæ which are reflexed to form the shank-portion 22 and the yielding toe or contact-portions 24. Bands 26 may encircle the shank-portions of the brush members, whereby to hold the laminæ in assembled form and, in addition, the laminæ may be soldered together and to the bands at the shanks.

The brush members are secured, preferably removably, to the opposite ends of the bar 18, by suitable means as bolts 28, in such a manner that the toe-portions 24 thereof are directed inwardly toward each other.

Fixed and removable arcing members 29

and 31 respectively are carried by the stationary and movable switch members and are arranged normally to shunt the main current carrying members when the switch is closed, and receive the circuit-interrupting arc, as the switch opens under load.

As thus arranged, the movable switch member is adapted to be raised to bring the contact faces 30 of the brush members against the contact faces 16 of the fixed contact members with considerable pressure, and the brush members are adapted to yield inwardly against the contact pressure.

As thus arranged, the magnetic reaction on the toe-portion 24 of the brush member, by the current traversing the toe and shank-portions of the brush-member, is to urge the toe-portions against the fixed contact members; or the effect is to increase the contact-pressure under load. The stationary and movable switch members constitute a U-shaped conductor, the magnetic field about which, when carrying current, also tends to increase the contact pressure of the brush members, with increased current strength. The reaction between a stud and the toe-portion of a brush, considered alone, tends to weaken the contact pressure but is overbalanced, or neutralized, at least, by the other reactions tending to improve the contact pressure. As thus arranged, the contact pressure between the movable and stationary switch members is enhanced under load or, at least, the magnetic reactions tending to weaken the pressure are substantially neutralized.

Fig. 3 illustrates a modification in which the reaction between the stud and brush is utilized to enhance the contact pressure. In this modification, the fixed contact member 14^a is extended approximately horizontally to that side of the stationary switch member opposite the other stationary switch member, so that the current traverses the contact member approximately horizontally. The magnetic reaction between the contact member and toe-portion of the brush thus tends to force the toe-portion against the fixed contact member.

The construction may be otherwise modified without departing from the spirit of the invention.

I claim:

1. An electric switch including a pair of

fixed terminals, and a cooperating movable bridging member having a pair of opposed and inwardly directed brush members each of which is arranged to engage a separate one of said fixed terminals and has its laminations transversely disposed to the plane including said fixed terminals.

2. An electric switch including a pair of vertical stationary switch members terminated in contact members having horizontal faces, and a movable switch member disposed beneath said contact members and including an approximately horizontal intermediate section, and a pair of opposed upwardly and inwardly directed brush members one of which is carried at each end of said intermediate section and having substantially horizontal contact faces disposed to engage the horizontal contact faces of said fixed contact members.

3. An electric switch including a pair of stationary switch members terminated in contact members, and a movable switch member disposed beneath said contact members and including an approximately horizontal intermediate section, and an upstanding brush member carried at each end of said intermediate section, each of said

brush members having upwardly and inwardly directed toe-portions terminated in a horizontal contact face which is disposed to engage one of said fixed contact members.

4. A movable switch member for an electric switch including a horizontal intermediate supporting member, an upstanding brush member carried by and disposed at each of the opposed ends of said supporting member, said brush members having vertical shank-portions and integral, mutually convergent toe-portions terminating in substantially horizontal contact faces.

5. A movable switch member for an electric switch including an intermediate supporting member, and a pair of opposed brush members spaced apart by the length of said supporting member and having shank-portions carried by the opposed ends of said supporting member, said brush members also having toe-portions extended upwardly and inwardly toward each other above and in alignment with said supporting member.

In testimony whereof, I have signed my name to this specification.

GEORGE A. BURNHAM.
